UNITED STATES PATENT OFFICE.

JOHN A. SPENCER, OF REVERE, MASSACHUSETTS, ASSIGNOR TO SPENCER THERMO-
STAT COMPANY, OF CAMBRIDGE, MASSACHUSETTS, A CORPORATION OF MASSA-
CHUSETTS.

CIRCUIT-INTERRUPTING DEVICE.

Application filed February 26, 1925, Serial No. 11,751. Renewed February 21, 1928.

My invention relates to circuit-interrupting devices and particularly to thermally-actuated switches.

One object of my invention is to provide a thermally actuated switch of relatively simple and effective construction.

In practicing my invention, I provide a pair of substantially circular supporting plates having a central tubular clamping member, a pair of discs of electric-insulating material, of different diameters, located thereon, and a plurality of contact plates located against said discs and held thereagainst by means projecting through said circular plates and discs. A thermostatic disc having a plurality of contact bridging members mounted thereon, is supported by a threaded rod projecting through and supported by the tubular clamping member and adjustable relatively thereto.

In the single sheet of drawings,

Figure 1 is a top plan view of a switch mechanism embodying my invention, parts thereof being cut away,

Fig. 2 is a view in section therethrough, taken on the line II—II of Fig. 1,

Fig. 3 is a fragmentary sectional view therethrough, taken on the line III—III of Fig. 1,

Fig. 4 is a top plan view of a supporting plate device,

Fig. 5 is a sectional view therethrough, taken on the line V—V of Fig. 4,

Fig. 6 is a bottom plan view of the parts shown in Fig. 4,

Fig. 7 is a top plan view of an insulating assembly and

Fig. 8 is a sectional view therethrough, taken on the line VIII—VIII of Fig. 7.

A switch mechanism designated generally by the numeral 11, is illustrated in top plan view in Fig. 1 of the drawing, and comprises a bottom supporting plate 12, a top supporting plate 13, each having a central aperture therethrough, within which there is located a tubular clamping member 14. The clamping member 14 is provided with an annular shoulder at the bottom thereof and is made substantially longer than the combined thickness of the two plates 12 and 13, to secure the two plates in proper operative position in face to face relation. The periphery of the upper end of the tubular member 14 is compressed to provide an annular portion 15

overhanging the top plate 13 in substantially the manner illustrated in Fig. 5 of the drawing.

The plate 12 is provided with a plurality of spaced openings 16, and the plate 13 is provided with a plurality of spaced openings 17, the openings 17 being coaxial with the opening 16, and of smaller diameter.

An insulating-member assembly 18 is illustrated in Figs. 7 and 8 of the drawing and comprises a disk of electric-insulating material 19, the diameter of which is slightly less than the diameter of the plate 13. A second disk 21, of electric-insulating material is located against one face of the member 19, the two members being provided with central axial openings 22 therethrough to receive a metal member 23, of tubular shape, that is provided at one end thereof with an annular shoulder 24 and that has the other end portion thereof turned over as illustrated by the numeral 25 in Fig. 8 of the drawing to securely clamp the two discs in coaxial and closely adjacent positions relatively to each other. The discs 21 and 19 are preferably made of mica and, when secured together by the use of the tubular member or thimble 23, they may be considered as an insulating-member assembly that is easily handled.

The disk 19 is provided with a plurality of openings 26 therein, that are so spaced as to be coaxial with the openings 16 and 17 in the supporting plates 12 and 13 in one position of the insulating-member assembly peripherally of the supporting plate aggregate.

A plurality of contact plates 27, 28, 29 and 31 are operatively supported by the supporting plate assembly and are located against the outer surface of the disk 19. The contact plates 27 to 31, inclusive, are of substantially arcuate shape, the inner edges thereof having such radii that they operatively engage the outer periphery of the disk 21, and any turning movement in the plane of the contact plate is prevented thereby.

Means for securing the respective contact plates against the supporting plate and the insulating-plate assembly comprises rivet members 32 having an enlarged head 33, and extending through the respective coaxial openings 16 and 17 in the plates 12 and 13, a disk 34 of electric insulating material, such as mica, serving to insulate the head 33 from the plate 13, and serving also to position the

body of the rivet 32 in the opening 17 and to maintain it coaxial therewith. This construction is more particularly shown in Fig. 3 of the drawing.

5 The contact plates hereinbefore described are disclosed and claimed in a copending application, Serial No. 11,895, filed February 26, 1925, by L. K. Marshall, and assigned to the Spencer Thermostat Company.

10 The switch of the present construction is more particularly applicable to, and employed with, thermostatic actuating means for effecting the control of the energizing circuit of an electrically heated device. A thermostatic disc 35 that comprises two metals having relatively different temperature expansivities is adjustably mounted in substantially parallel-spaced relation to the supporting plate assembly. This mounting comprises 15 a shouldered screw-threaded stud 36 that projects through the internally screw-threaded tubular clamping member 14 and that has a flanged member 37 located close to one end thereof. A fixed nut 38 is provided 20 adjacent to, but spaced from, the flange 37 and the disc 35 is loosely mounted therebetween to permit of a turning movement of the stud 36 relatively to the internally screw threaded tubular member 14 to permit of varying 25 the distance of the thermostatic disc and of other members carried thereby toward and away from the contact plates hereinbefore described.

The end of the stud 36 is provided with a 30 portion 39 of reduced thickness that may be made of substantially rectangular form in section, in order to permit of holding the stud 36 while a lock-nut 41 is tightened to prevent any further turning movement of the stud 36 35 after proper adjustment has once been made.

A plurality of contact bridging members 42 are supported by the thermostatic disc 35, by means of a stud member 43 that has an intermediate portion of enlarged diameter 45 which fits against a disk 44 of electric-insulating material, such as mica. A disc 45 of electric-insulating material is so located against a surface 35^a of the thermostatic disc 35 as to register with an opening 46 therein, 50 through which a portion 43^a of the stud 43 may extend. A small metal disc 47 is located against the outer surface of the disc 45 both of which register with the portion 43^a. An end portion 43^b of the stud member 43 may be 55 peened over in order to securely clamp the contact bridging member in its proper operative position, relatively not only to the thermostatic disc, but also to the spaced ends of the fixed contact plates which it is to operate 60 engag. The disc member 47 is slightly dished inwardly during the peening operation which effects a location of the intermediate portion of the stud 43 coaxially with the opening 46 through which it projects.

65 The contact bridging members 42 are loose-

ly mounted on the lower portion of the studs 43, as is more particularly disclosed and claimed in my copending application, Serial No. 565,255, filed June 1, 1922, and assigned to the Spencer Thermostat Company.

70 The contact plates 27 and 31, are not secured in their proper operative position by means of short rivets as are the plates 28 and 29, but by the use of studs that have a depending projection 48 to permit of connecting thereto the ends of suitable supply circuit conductors in a manner well known in the art. In all other respects, the studs 48 are of the same general construction and have 75 the same effect as the rivets 32.

80 In order to insure that the thermostatic disc 35 shall not move circumferentially relatively to the supporting plate, a locating means is provided, which comprises a stud having an enlarged lower portion 49 that fits into coaxial 85 aligned openings 51 and 52 provided in the respective plates 13 and 12. To hold the member 49 in its proper operative position relatively to the plates 12 and 13, a punch member is employed to head-over the rim portion thereof that is located in substantially the same plane as the upper surface of the plate 13, as is more particularly illustrated in Fig. 2 of the drawing. The member 49 has a portion 53 of relatively smaller diameter 90 than the lower portion projecting upwardly therefrom and through an opening 54 in the disc 19 and through an opening 55 in the thermostatic disc 35.

95 The thermostatic disc 35 is provided with a non-developable surface, substantially as described in my U. S. Letters Patent No. 1,448,240, such that when the disc is subjected to a predetermined temperature, the unequal expansion of the metals comprising the 100 disc causes it to suddenly reverse the curvature of its non-developable surface to thereby disengage the contact bridging members 42 from the contact members 27, 28, 29, and 31, simultaneously. Upon cooling of the disc 105 35 to a predetermined temperature, the unequal contraction of the metals comprising the disc causes it to suddenly assume its initial position, as illustrated in Fig. 2 of the drawings.

110 The device embodying my invention thus provides a relatively small supporting-plate assembly and an insulating disc assembly which cooperate with each other to support a plurality of contact plates of arcuate form 115 in proper operative positions against one surface of an insulating disc of larger diameter and against the outer periphery of an insulating disc of smaller diameter. Small insulating discs located in openings in the lower 120 of a pair of supporting plates, serve also to properly position the securing means coaxially in the openings and supported by the metal supporting plates.

125 It is evident that any turning movement 130

of the contact plates in the plane of the plates themselves, is effectively prevented by the operative engagement of the inner periphery surface thereof with the insulating disc of 5 smaller diameter.

The device embodying my invention provides also relatively simple means for operatively supporting a plurality of contact bridging members that are normally in operative engagement with the contact plates in such manner that adjustment thereof toward and away from the contact plates is easily effected, whereby, in the present construction, it is possible to vary the temperature at which 15 the thermostatic disc will operate to interrupt the circuit through the plurality of contact plates.

While not hereinbefore specifically mentioned, it may be here stated that this switch 20 mechanism provides a circuit interrupting means whereby the circuit is simultaneously interrupted at six contact points. That is, the current path is over the plate 27 and through the operating bridging member and 25 the plate 28, from there through the cooperating bridging member to plate 29 and from there to a cooperating bridging member to the plate 31 and to the other conductor of the supply circuit.

30 Since various modifications and changes may be made herein without departing from the spirit and scope thereof, all such modifications are intended to be covered by the appended claims.

35 I claim as my invention:

1. A switch comprising a pair of supporting plates in face-to-face relation, a tubular clamping member for holding said plates together, a plurality of contact plates insulated 40 mounted on said supporting plates, a plurality of contact bridging members normally operatively engaging said contact plates, and means projecting through said clamping member for operatively supporting said contact bridging members.

2. A switch comprising a pair of supporting plates in face-to-face relation, a tubular clamping member for holding said plates together, a plurality of contact plates insulated 50 mounted on said supporting plates, a plurality of contact bridging members normally operatively engaging said contact plates, and means adjustably supported by said clamping member for operatively supporting said contact bridging members.

55 3. A switch comprising a pair of supporting plates in face-to-face relation, a tubular clamping member for holding said plates together, a plurality of contact plates insu-

latedly mounted on said supporting plates, a 60 plurality of contact bridging members normally operatively engaging said contact plates, and means for adjusting the same toward and away from said contact members.

4. A switch comprising a plurality of supporting plates, a tubular clamping member for holding said plates together, a plurality of discs of electric-insulating material and of different external diameter located against the outer face of one of said supporting 70 plates, a plurality of contact plates of substantially arcuate contour located on the insulating disc of larger diameter and abutting the periphery of the smaller disc, a plurality of contact bridging members normally operatively engaging said contact plates, and means projecting through and supported by said tubular clamping member for normally operatively supporting said contact bridging members.

5. An electric switch comprising a base of 80 a plurality of layers of metal, means for clamping said layers together, an electric switching mechanism, and means cooperating with said clamping means for supporting 85 said switching means.

6. An electric switch comprising a base composed of a plurality of layers, stationary contacts insulatedly mounted thereon, clamping means for holding said layers together, 90 a plurality of movable contacts, thermostatic means for actuating said contacts, and means cooperating with said clamping means for supporting said thermostatic means.

7. A switch comprising a laminated base 95 having stationary contacts thereon, means for holding said laminations together, a movable thermostatic member carrying a plurality of contacts, and means cooperating with said holding means for supporting said member on said base.

8. The device of claim 7 wherein said cooperating means may be adjusted.

9. A thermostatically controlled switch comprising a plurality of cooperating stationary and movable contacts, a thermostatic element, said movable contacts being mounted on said element, cooperating contacts being adapted to be simultaneously opened and closed, a metal base in heat conducting relation to said element, and means for insulatedly mounting said stationary contacts on said base.

In testimony whereof, I have hereunto subscribed my name this 20th day of February, 115 1925.

JOHN A. SPENCER.
